MOVABLE ROOF STABILIZER

Filed May 20, 1944

UNITED STATES PATENT OFFICE

2,436,580

MOVABLE ROOF STABILIZER

Wilbur G. Laird, Pleasantville, N. Y.

Application May 20, 1944, Serial No. 536,493

10 Claims. (Cl. 48—176)

1

This invention relates to improvements in apparatus for storing liquids or gases or both, and more particularly to tanks or containers provided with a vertically movable roof such as a lift or bell, or other type of roof in combination with means for guiding the roof.

This application is a continuation-in-part of application Serial No. 448,822, filed June 27, 1942.

The expansion roofs of large oil storage tanks must be guided in their vertical movement to prevent tipping. The guiding or stabilizing means of the present invention is particularly adapted for controlling the movement of lifts, bells and other types of roofs for either liquid or gas storage apparatus and may be used regardless of the sealing means by which the roof is sealed with respect to the body of the tank or container.

The primary object of the present invention is to provide an improved storage apparatus in which a novel stabilizing means is provided for the roof.

A further object of the invention is to provide a roof stabilizing means which may be mounted entirely outside the roof and container and therefore be readily accessible for repairs and inspection, and be out of contact with the fluid or fluids stored in the apparatus. The stabilizing means may be mounted inside the container if desired.

Accordingly, the storage apparatus of the present invention comprises an upright cylindrical type container or tank, a roof for the fluid to be stored therein which is movable vertically with changes in the volume of fluid in the tank or container, and means for guiding the roof or stabilizing it from substantial tilting or tipping, said means including at least three hydraulic plunger units distributed around the tank and roof with a plunger of each unit connected by a rigid connection to the roof while the unit proper remains stationary, and conduits for the passage of hydraulic liquid from one unit to another. The hydraulic units may be arranged in pairs, at least two pairs being necessary to stabilize a roof.

The pending application referred to discloses the use of distributed hydraulic units of the type described, that is, a plurality of sets or pairs, cross-connected, for maintaining parallel motion of a portion of a vertically movable roof for a storage tank. Each of the units includes spaced upper and lower cylinders mounted in vertical alignment and in fixed position with respect to each other by means of a solid frame. Each unit is provided with a plunger which extends into the cylinders through end packing glands, the

2

plunger being provided with a central lug by which the plunger is connected to the peripheral portion of the roof to be kept horizontal. The lower cylinder of each pair of units or control mechanism is connected by a conduit to the opposite upper cylinder.

Said application discloses that the cylinders are provided with plungers of equal displacement, and all cylinders and lines filled with oil or other pressure transmitting liquid. The plungers are all connected to the same peripheral part of the roof. When the plungers are forced into the lower cylinders they cause liquid to be forced through the conduits into the opposite upper cylinders. The plungers have the same diameter and displacement so that the quantities of pressure medium forced from the lower cylinders into the opposite upper cylinders are the same. Two or more pairs of the units distributed around the roof insure parallel motion, because no plunger can move unless the plunger of the opposite connected unit moves to the same extent and in the same direction.

The detailed features and advantages of the present invention will be apparent to those skilled in the art from the following detailed description thereof taken in connection with the accompanying drawings in which:

Fig. 1 is a broken front view partly in vertical section of a storage apparatus for fluids constructed in accordance with and illustrating one form of the invention.

Fig. 2 is a broken horizontal sectional view of a part of the apparatus shown in Fig. 1, taken on the line 2—2.

Fig. 3 is an enlarged sectional view of the expansion relief chamber shown in Fig. 1.

Fig. 4 is a diagrammatic view showing a modification of the arrangement of the plunger units shown in Fig. 1.

Referring to Figs. 1 and 2 of the drawings, the apparatus illustrated is of the type used for the storage of petroleum products such as crude oil and gasoline, and comprises an upright cylindrical steel shell 10 having a bottom plate 12 (Fig. 2). The shell 10 supports a trough or launder 14 having an inner wall 16 provided with a top curb 18. The launder 14 holds a sealing liquid and extends entirely around the upper portion 50 of the shell which serves as the outside wall of the launder. The launder is shown inside the shell but may be outside if desired, although it is somewhat more convenient to have it inside in the present instance. The tank roof comprises a cambered or cone-shaped plate 20 having a sub-

stantially flat section 22 which extends over the launder 14 and which may be integral with the roof plate 20, or an attached continuation. The roof also includes an annular or cylindrical sheet metal curtain wall or apron 24, which is secured to the roof plate 20 in a fluid-tight manner, and which seals in the liquid in the launder 14. The roof may also be provided with a weather hood 26 which may be bolted or otherwise fastened to the edge of the plate 22.

The bell-type lift as shown moves up and down, according to the changes in volume of the liquid or vapor in the container. These changes may be caused by changes in the atmospheric conditions or by the introduction of or withdrawal of the stored fluids. Containers or expansion roof tanks of this type prevent loss of valuable volatile constituents which would be lost by evaporation if stored in open tanks.

According to the features of the present invention the roof or lift is kept in its normal path of up and down movement and prevented from tipping by a stabilizing means comprising a plurality of pairs of hydraulic units or a distributed series of three or more such units. A pair of interconnected hydraulic units are shown in Figs. 1 and 2, which are similar to those in said pending application, the units being mounted on opposite sides of the tank in connection with vertical beams 28. The upper ends of these beams as illustrated are attached to the roof plate 22 inside the weather hood 26 by welding or other suitable means. These beams may be of any desired cross-section but are preferably of the channel section shown in Fig. 2, and provided with track flanges 32 which operate between a pair of flanged rollers 34 mounted on spaced brackets 36 attached to the top of the shell 10.

Each of the hydraulic units includes similar upper and lower pressure cylinders or barrels 38 and 40 mounted in spaced vertical alignment and fastened to the shell 10 in fixed relation to each other by means of brackets 42. Other fastening means may be used at the top of cylinder 38 and at the bottom of cylinder 40. The space between the cylinders 38 and 40 of a unit is slightly greater than the distance through which the roof moves. Each unit is provided with a plunger or ram 44 which extends into the cylinders 38 and 40 through end packing glands 46, the mid-portion of the plunger being connected to the lower end of a beam 28 by means of a lug or other connector 48, adapted to take an up and down thrust. The lower cylinder of each pair of units is connected through a pipe 50 with the opposite upper cylinder of that pair so that liquid may flow freely between them. Portions of the line 50 are indicated by dotted lines across the part of the apparatus shown in section in order to indicate the connections. The cylinders 38 and 40, and lines 50, are filled with liquid, and since all plungers are of the same diameter and displacement, the liquid forced from one cylinder, a lower cylinder, for example, into the opposite upper cylinder, will cause the plunger therein to move down through the same distance that the opposite plunger moves down, to give place to the exact amount of liquid forced from the opposite lower cylinder. In this operation the opposite plungers will move in the same direction, the same vertical distance, and the same volume of liquid will be forced from all lower cylinders and forced or drawn into the respective opposite upper cylinders. The opposite sides of the roof will therefore be kept at the same level and parallel to the top of the tank.

If the plunger of one unit is forced down by the roof, it forces liquid from the lower cylinder and draws liquid into the upper cylinder, thereby affecting the connected unit to draw liquid from the lower cylinder and force liquid into the upper cylinder which causes the plunger therein to move down.

Two or more pairs of these plunger and cylinder units distributed around the roof insure parallel motion because no plunger can move unless the plunger of the opposite connected unit moves to the same extent and in the same direction. The distributed connected pairs of units also provide a cushioning means for the roof because liquid must be moved through the lines 50 when the roof moves up or down.

The upper portion of each pipe 50, and the associated cylinders are connected into a relief chamber 52 by a connecting line 54. Each chamber 52 is provided with a breather vent 56. The structure and function of the relief chambers 52 is shown in Fig. 3, in which the line 54 is shown as extending into the chamber 52 and equipped with a set of valves for maintaining the line 50 and its associated cylinders filled with oil or other liquid under various temperature conditions. The line 54 in the chamber is provided with a cut-off valve 58, controlled by a float 60. At the top of the line 54 is a pressure relief valve 62 of conventional type adapted to operate to release oil from the line 50 at a predetermined maximum pressure. The line 54 is also provided with an oil return check valve 64 near the bottom of the chamber so that its inlet is always covered with oil or other liquid. The valve 64 is connected into the line 54 below the float valve.

Since it is apparent that the liquid in the plunger units will expand when its temperature rises, and contract when its temperature falls, the chamber 52 is filled with sufficient liquid to take care of any possible contraction of the liquid, which is drawn into the line 54 and line 50 through the check valve 64. When the temperature of the liquid rises and it expands to create a predetermined maximum pressure in the cylinders 38 and 40, the valve 62 is operated automatically to release liquid into the chamber 52 to compensate for the expansion of the liquid. If desired float controlled valve 58 may be omitted, but it serves as indicated, to prevent the release of more liquid through the valve 62 than that required to operate the float 60, so as to cut off the flow through pipe 54. The valve 58 is preferably included in the assembly. The closing of the valve 58 may cause the pressure to build up somewhat but prevents release of an excessive quantity of liquid from the plunger units. The plunger units will stand extremely high pressures. The valve 62 is preferably set to open only at a relatively high pressure of, for example, from 500 to 1000 pounds per square inch where three or four inch diameter plungers are used. Other means may be used to automatically release liquid, and other means may be used to return liquid to the cylinders automatically.

Instead of arranging the plunger units in pairs as in Fig. 1, they may be arranged in series around the roof and tank as shown diagrammatically in Fig. 4. In this arrangement the plunger units are mounted at distributed positions around the tank and the plungers connected to the roof as in Fig. 1. The lower cylinder of each unit is connected by a pipe 66 with the upper cylinder of the next unit in the series in one direction around the tank so that an endless series is

formed. Each of the connecting pipes 66 is provided with a relief chamber 52 as in Fig. 1. In this modification the plungers, and the roof to which they are connected, must move in unison in the same direction and to the same extent because the liquid in the cylinders is substantially incompressible, and is adapted to flow through a line 66 in either direction between the lower cylinder of one unit and the upper cylinder of an adjacent unit.

The plunger units may be interconnected in other ways than that shown in Figs. 1 and 4 to insure the proper guiding of the roof in its up and down movements with respect to the tank or storage container. Furthermore, the units may be mounted inside the container and at any desired level, although it is preferred to have them outside the container so that they will be accessible for inspection and repair. The plungers may be connected to the roof by any suitable means adapted to take the up and down thrust, other than the beams 28, and the units may be suitably combined with other roof stabilizing or guiding means. The securing of the plunger unit cylinders to the stationary part of the apparatus, combined with the beams 28 and guide rollers 34, provide a very effective vertical guide means for controlling an expansion or movable roof. However, the plunger may be the fixed member while the barrels move if such an arrangement is desired.

The connecting pipes or lines 50 and 66 may be provided with connections (not shown) for filling, and the cylinders may be provided with suitable valved air vents at the top for venting air or other gas when the units are initially filled with liquid. The lines 50 or 66 may be mounted on the outside of the tank or may extend across through the tank, below the roof. It might be of considerable advantage in the case of the lines 50 to have them go straight through the tank since they would be shorter and about on a diameter. They could be supported by the inside roof supports which are almost always necessary for tanks of any substantial diameter. Where the pipes pass through the tank wall they may be welded in the wall or otherwise extended through by a fluid-tight joint or be extended through a pipe casing. The pipes may be connected into any part of the cylinders or barrels 38 and 40, which need not be accurately sized, machined inside, or of the same capacity.

The cylinders or barrels 38 and 40 may be made by welding heads on suitable lengths of standard steel pipe of the selected diameter. The plungers may be made from solid billets or of pipe lengths with plugged or welded-in ends, the pipe being machined to a uniform diameter, and plated or protected against corrosion. The liquid used in the hydraulic system is preferably a stable oil which will be fluid and non-volatile at all temperatures encountered, and of low expansion characteristics. The liquid may contain an anti-corrosion agent.

The stabilizing means of the present invention may be applied to various types of tanks or containers for liquids and gases or both, and to various types of roofs such as bells, decks, floating roofs and piston roofs. Where it is desired merely to store gases, a launder may be made of concrete in the earth, and the earth inside the launder gas-proofed and rounded to support the roof.

The stabilizing units adjacent each other around the apparatus may be arranged in pairs like the pair of units shown in Fig. 1, if desirable.

The plunger units may be mounted on the roof, if desired, and beams or other means used to connect the plungers to a fixed part of the apparatus. The cylinders of each unit are preferably arranged in line, one above the other, with a single plunger or ram operating therein, in the simple form described and illustrated, but it is apparent that they could be arranged horizontally or at some other angle if suitable leverage

means connects the plunger to the roof. Furthermore, the cylinders of a unit can be arranged otherwise than in a line, for example, at the same level and upright, if two interconnected plungers are used, only one of which would be connected to the roof, the same one in each of several units.

Two plungers in a unit of this type might be connected by a walking beam so that one plunger would draw in the same volume of liquid forced out by the other.

Further modifications may be made without departing from the invention.

Having described the invention in its preferred form, what is claimed as new is:

1. In a storage apparatus for fluids including an upright cylindrical container and a vertically movable roof sealed with respect to the container wall, a plurality of at least three spaced hydraulic stabilizing units distributed around the container, each of said units including a pair of vertically spaced chambers fixed to the container, a plunger extending into said chambers and vertically movable therein, connecting means between the mid-portion of each plunger and the roof, and a conduit from the lower chamber of each unit to the upper chamber of a different unit, the plungers of the units interconnected by a conduit being of equal displacement.

2. An apparatus for holding fluids, comprising a container including a vertically movable bell-type roof sealed with respect to the stationary part of the container, a plurality of at least three spaced hydraulic units for preventing the tipping of the roof, said units being distributed around the container and each unit including a pair of chambers for hydraulic liquid arranged with one spaced substantially above the other and attached to a fixed part of the apparatus, a plunger operating between and extending into the chambers of each pair and operative therein to replace liquid and be displaced by liquid, the mid-portion of each plunger being attached to the roof and operable thereby, a pipe connecting the lower chamber of each unit with the upper chamber of a different unit, and an expansion chamber connected with each two hydraulic chambers which are interconnected by a pipe, the plungers of the units connected by a pipe being of equal displacement.

3. An apparatus for holding fluids, comprising a container including a vertically movable bell-type roof sealed with respect to the stationary part of the container, a plurality of at least three spaced hydraulic units for preventing the tipping of the roof, said units being distributed around the container and each unit including a pair of charge and discharge chambers for hydraulic liquid upon a given vertical movement of the roof, said chambers being attached to a fixed part of the apparatus, plungers of equal displacement extending into the chambers of all units and operative therein by the roof to replace liquid and be displaced by liquid, a plunger of each unit being attached to the roof by a beam which is attached to the plunger between the chambers of the unit, and a pipe connecting the charge

chamber of each unit with the discharge chamber of a different unit.

4. In a storage apparatus for fluids including an upright cylindrical container and a vertically movable roof sealed with respect to the container wall, a plurality of pairs of hydraulic units distributed around the container, each of said units including spaced upper and lower upright cylinders for hydraulic liquid, a plunger extending between and into the cylinders of each unit, the plungers of each pair of units being of equal displacement, a connecting member between the roof and the midportion of each plunger for operating the plungers by the movement of the roof, and a pipe connecting the lower cylinder of each pair of units with the opposite upper cylinder of that pair of units.

5. In a storage apparatus for fluids including an upright cylindrical container and a vertically movable bell-type roof sealed in a laundress at the upper portion of the container wall, a plurality of pairs of hydraulic units distributed around the container with the units of each pair on opposite sides of the container, each of said units including substantially spaced upper and lower upright cylinders for hydraulic liquid attached to a fixed part of the apparatus, a plunger extending between and into the cylinders of each unit, the plungers of each pair of units being of equal displacement, a beam attached to the mid-portion of each plunger and to the roof, and a pipe connecting the lower cylinder of each pair of units with the opposite upper cylinder of that pair of units.

6. In a storage apparatus for fluids including an upright cylindrical tank and a vertically movable roof sealed with respect to the tank wall, a plurality of spaced hydraulic stabilizing units distributed around the tank, each of said units including a pair of vertically spaced chambers for hydraulic liquid fixed to the tank, a plunger extending between and into the chambers of each unit and vertically movable therein, connecting means between the roof and the mid-portion of each plunger, a conduit from the lower chamber of each unit to the upper chamber of a different unit, the plungers of units interconnected by a conduit being of equal displacement, an expansion chamber connected into each conduit for receiving hydraulic liquid upon a predetermined expansion of the hydraulic liquid, and means for returning hydraulic liquid to said conduit.

7. An apparatus for holding fluids, comprising a container including a vertically movable bell-type roof sealed with respect to the stationary part of the container, a plurality of at least three spaced hydraulic units for preventing the tipping of the roof, said units being distributed around the container and each unit including a pair of chambers for hydraulic liquid arranged with one spaced substantially above the other and attached to a fixed part of the apparatus, a plunger extending into the chambers of each pair and operative therein to replace liquid and be displaced by liquid, the mid-portion of each plunger being attached to the roof, and a pipe connecting the lower chamber of each unit with the upper chamber of a different unit, the plungers of units interconnected by a pipe being of equal displacement.

8. An apparatus for storing fluids, comprising a container including a vertically movable roof sealed with respect to the container, a stabilizing means for keeping the roof from tipping including at least three interconnected hydraulic units distributed around the container and roof and connected to each, each unit including a pair of spaced chambers for hydraulic liquid and a plunger operative therein to force liquid from one chamber when the roof moves up and to force liquid from the other chamber when the roof moves down, one of the elements of each unit consisting of said pair of chambers and said plunger being attached to said container and the other element being attached to the roof, the attachment to the plunger being between said chambers, said plungers being of equal displacement, and a connecting pipe between each chamber of each unit and the oppositely acting chamber of a different unit whereby liquid forced from one chamber is introduced into the oppositely acting chamber of a different unit.

9. In a storage apparatus for fluids including a container having a vertically movable roof sealed with respect to the stationary part of the container, a plurality of at least three spaced hydraulic stabilizing units distributed around the container and connected to a fixed part of the apparatus and to the roof, each of said units including a pair of chambers for hydraulic liquid each of which has a plunger extending thereto, the plungers of each pair of chambers being interconnected for opposite motion with respect to the chambers into which they extend, one of the elements of each unit consisting of said pair of chambers and said plunger being attached to said container and the other element being attached to the roof, the attachment to the plunger being between said chambers, a pipe connecting each chamber of each unit with the oppositely acting chamber of a different unit, the plungers in the chambers connected by a pipe being of equal diameter, an expansion relief chamber connected into the chambers connected by said pipe and including means for accepting liquid from said chambers at a predetermined pressure, a float controlled valve in said expansion relief chamber, and means for returning liquid from said expansion chamber to said pipe-connected chambers in response to a contraction of the liquid therein.

10. In a storage apparatus as defined by claim 1 in which an expansion relief chamber is connected to each conduit, said chamber including means for accepting liquid from said chambers at a predetermined pressure, a float-controlled valve in said expansion relief chamber, and means for returning liquid from said expansion relief chamber to said conduit-connected chambers in response to a contraction of the liquid therein.
